W. B. KING,
PRESS.
FILED JUNE 13, 1919.

UNITED STATES PATENT OFFICE.

WILLIAM B. KING, OF NEEDHAM, MASSACHUSETTS, ASSIGNOR TO UNITED SHOE MACHINERY CORPORATION, OF PATERSON, NEW JERSEY, A CORPORATION OF NEW JERSEY.

PRESS.

Application filed June 13, 1919. Serial No. 303,998.

To all whom it may concern:

Be it known that I, WILLIAM B. KING, a citizen of the United States, residing at Needham, in the county of Norfolk and 5 State of Massachusetts, have invented certain Improvements in Presses, of which the following description, in connection with the accompanying drawings, is a specification, like reference characters on the drawings indicating like parts in the several figures.

This invention relates to improvements in presses of that type in which a pressure applying member is movable into various positions relative to a bed to apply pressure to different parts of stock located between the pressure member and the bed. While presses of this type may be used for many different purposes, they are often used for 15 dieing-out sheet material, and accordingly I have shown my invention applied to a press of this kind, it being understood that it is by no means limited to use with machines for accomplishing this result.

20 An important feature of this invention relates to the provision in a press of the character described of improved power means for moving the presser member laterally over the work supporting bed, the construction providing preferably a manually controllable member mounted on the presser member and operable to control the said power means.

25 Practically all types of presses are provided with power means for causing pressure applying movements of the movable presser member, manually operable means being employed for controlling the power means. It is an object of the present invention to provide a single manually operable means for controlling both the power means for causing lateral movement of the presser member over the work supporting bed and the power means for effecting the pressure 30 applying operations of the presser member, the said manually operable means being preferably mounted on the presser member for movement therewith, thus providing a controlling means easily accessible to the operator and readily operable to effect the 35 movements of the presser member in proper sequence.

Another important feature of the invention relates to improvements in a type of 40 press which comprises a work supporting

bed and a presser member mounted on a post for rotation about the axis of the post in such manner that the presser member may be made to occupy various operative positions with respect to work on the work supporting bed, the improvements residing in a simple, compact and most efficient power means for rotating the presser member about the axis of the post comprising a device mounted for rotation on the post and 45 providing a moving surface to which the presser member may be operatively connected at the will of the operator to swing the presser member over the work supporting bed. Preferably two such devices are 50 mounted on the post for rotation in opposite directions, means being provided for selectively connecting the presser member thereto whereby the latter may be moved in the desired direction over the work on the 55 support.

Another feature of importance relates to an improved starting mechanism for controlling the power means for effecting the pressure applying operations of the presser 60 member. Preferably this mechanism comprises a lever mounted on the frame of the machine and having an arcual portion which provides a contacting surface for a single roll carried by another lever mounted 65 on the presser member, the construction and arrangement being such that the roll remains in contact with the arcual surface in all positions of the presser member and without any tendency to a binding action during 70 movements of the latter.

A principal feature of the starting mechanism resides in the provision of a handle for the mechanism mounted on the presser member and so arranged as to remain substantially stationary in space during the reciprocation of the presser member in a pressure applying operation, whereby the hand of the operator receives no objectional thrust from the handle during the operation 80 of the machine.

Other features and objects of the invention will be apparent from the following detailed description and will be pointed out in the claims.

In the drawings:—

Figure 1 is a view in side elevation of the illustrative machine;

Fig. 2 is a fragmentary view showing the course of the cable about the idlers and the 90

pulleys on the supporting post of the presser member;

Fig. 3 is a detail of the starting mechanism; and

5 Fig. 4 is a section of the presser member in front of the operating pulleys and showing the attachments of the pulley bands to the presser member.

In the illustrative embodiment of the invention there are shown a work supporting bed 6 and a presser member 8 movable laterally over the work supporting bed into different operative positions with respect to the work on the bed. Mounted in bearings 10 and 12 of the frame 14 of the machine is a post 16 which supports the presser member 8 for rotation about the axis of the post. Preferably, and as shown, the presser member 8 is fixedly secured to the post 16, and 15 upon reciprocation of the latter vertically the presser member is caused to approach and recede from the work supporting bed in pressure applying operations upon work on the bed. Mounted in the frame of the machine is a shaft 18 operatively connected to the post 16 by means not shown but which may be according to the construction disclosed in the patent to Arthur Bates, No. 921,503, granted May 11, 1909, said shaft 20 carrying a power pulley 20, clutching mechanism being provided for connecting the shaft to the power pulley at the will of the operator, the said clutching means being preferably housed in a casing 22 and being 25 of a well-known type of one-revolution clutch mechanism preferably, though not necessarily, like that shown in said patent. Starting means under the control of the operator for causing operation of the machine 30 as desired comprises a lever pivoted on the frame of the machine and connected by a link to the clutch mechanism so that upon 35 operation of the lever the clutch may be tripped and thus cause operative connection 40 of the shaft and power pulley.

An improved form of starting means comprises a lever 24 pivoted at 28 to the upper part of the frame of the machine and having at its forward end an arcual portion 30 extending in front of the upper bearing 12. By this arrangement of the tripping lever the bearing 32 of the presser member 8 may be made as deep as desired, since no part 45 of the lever is interposed between the presser member and the bearing 12, the construction and arrangement differing in this respect from that shown in said patent to Bates. In other words, the bearing may be extended 50 along the post 16 practically into contact with the lower surface of the frame bearing 12 when it is desired to make the presser member 8 especially heavy and give it a deep bearing on the post. In co-operation 55 with the lever 24 there is provided a lever device mounted on the presser member, the con-

struction being such that the device on the presser member engages the upper surface only of the arcual portion 30 of the lever 24, thus providing against any tendency of a binding action between the engaging portions as the presser member moves about its axis of support. Preferably, the lever device on the presser member comprises two levers 34 and 36 mounted on pivot supports 38 and 40 respectively, the supports being 60 vertically adjustable as indicated by set screws 42 provided for securing the supports in adjusted position. The arms *a*, *a'* of the lever 34 are equal in length in the horizontal direction as also are the arms *b*, *b'* 65 of the lever 36, it being immaterial whether or not the arm *a* is equal in length to the arm *b*. As shown, the arm *b'* of lever 36 carries a roll 44 for engaging the upper surface of the arcual portion 30 of the lever 24. At the 70 other end of the lever device, the arm *a* of the lever 34 carries a handle member 46 having shoulders or collar portions 48 for engaging the upper and lower surfaces of the 75 end of the lever arm *a*. In order that the handle 46 may move laterally with respect to the lever 34, the said lever is provided with a slot extending transversely of the end of the lever, the arrangement of the handle and elongated slot having a purpose which 80 will be later pointed out in connection with means for moving the presser member laterally from and into position over the work 85 supporting bed.

An intermeshing gear tooth connection is 90 provided at *c* between the adjacent ends of the levers 34 and 36, and upon depression of the handle 46, the lever device just described will operate through the roll 44 to 95 depress the arcual portion 30 of the lever 24 and thus trip the clutch on the main shaft of the machine. After the clutch is tripped the presser member moves downwardly in a pressure applying operation carrying with it the pivots 38 and 40 of the levers 34 and 100 36. As the roll 44 cannot move downwardly with the presser member 8, the lever 36 swings about its pivot 40 causing the adjacent connected arms *a'* and *b* of the levers 105 34 and 36 to move downwardly and the other 110 arm *a* of lever 34 to move upwardly carrying the handle 46 upwardly away from the presser member 8 a distance equal to the amount that the presser member is depressed in its pressure applying movement. 115 In other words, the downward movement of the presser member produces no movement of the handle 46 which is pivotally carried thereby, this being due to the fact that the horizontal lengths of the arms of the 120 levers are equal, *a* to *a'* and *b* to *b'*. This construction and arrangement of the starting means removes any tendency of the handle 125 of the lever mounted on the presser member to strike or thrust against the hand of the 130

operator, it being clear that the handle remains practically stationary in space during a complete reciprocation of the presser member. Another important advantage of 5 the starting means resides in the construction by which no binding action takes place between any of its parts during movement of the presser member laterally over the work support or upon reciprocatory movement 10 toward and from the work support.

In most of the presses as at present constructed, the presser member is moved laterally over the work supporting bed by force exerted directly by the operator. When the 15 presser member is particularly heavy and in other constructions also, it is desirable to provide power means for moving the presser member laterally over the bed thus lessening materially the labor involved in operating 20 a press of this kind. In the illustrated machine, the power means for moving the presser member comprises connections with the power pulley on the main shaft of the machine so constructed and arranged as to 25 impart lateral movement to the presser member at the will of the operator. In the construction shown, the pulley 20 is provided with a pulley 50 formed integrally therewith or securely attached thereto and 30 about which passes an endless cable 52. There are provided also pulleys 54 and 56 mounted preferably on the post 16 and arranged to be driven constantly in opposite directions by means of the cable 52. The 35 upper run 58 of the cable 52 passes over an idler 60 and thence around the upper pulley 54 in a groove therein and from there to an idler pulley 62 mounted on the frame of the machine. The cable passes around this 40 idler 62 and thence as the lower run 64 of the cable it passes around the lower pulley 56 in a groove therein and thence to and over an idler 66 to extend to and become continuous with the cable passing around 45 the pulley 50. In the construction shown, the idlers 60 and 66 are mounted upon a bracket 68 extending from the frame of the machine, the pulley 62 being mounted preferably in a slidable bearing (not shown) on 50 the frame 14 so that it may be adjusted to take up any slack in the cable 52. Upon tracing the course of the endless cable 52 it will be seen that the upper pulley 54 turns in the opposite direction to the lower pulley 55 56, thus providing surfaces moving in opposite directions to which the presser member may be operatively connected when it is desired to move the presser member into and out of position over the work supporting 60 bed. In the illustrative construction, the connections between the presser member and the pulleys 54 and 56 comprise a lever 70 pivotally mounted at 72 upon a web 74 in the presser member 8, the free end of 65 the lever receiving for vertical sliding move-

ment therein the lower end of the handle 46. Fixedly attached to or integral with the other end of the lever 70 is a pin 78 extending vertically across said end so as to provide an upper and a lower pin or post 70 to which are connected means passing around the described moving surfaces and attached to the presser member for selectively connecting the presser member to said surfaces, the said means comprising preferably relatively wide bands 80 and 82, the upper band 80 passing around a pulley member 84 fixedly attached to or integral with the upper pulley 54 while the lower band 82 passes around a corresponding pulley member 86 similarly secured to the lower pulley 56. One end of the band 80 is secured to a pin or bolt 88 fixedly carried by the presser member 8 while the other end of the same band is wrapped around or otherwise secured to the upper pin or arm 78 horizontally aligned with the bolt 88 and located on the lever 70. The lower band 82 is similarly secured to the presser member and to the lever by having one end secured 90 to a pin or bolt 89 on the presser member and its other end to the lower pin or arm 79 horizontally aligned with bolt 89 and carried on the lever 70, the end of the band 82 secured to the presser member being attached in a lower plane and laterally of the point of attachment of the upper band to the presser member, as will be clear from an inspection of Figs. 2 and 4 of the drawings. Referring to Fig. 2 of the drawings, 100 it will be seen that when the lever 70 is moved about its pivot 72 so that the pin 78 carried thereby is moved to the right in the said figure that the upper band 80 is tightened about its pulley and thus the 105 presser member 8 is carried in the direction of rotation of the pulley, movement of the presser member taking place about the axis of the post 16. On the other hand, when the lever 70 is moved in the other direction 110 about its pivot 72, the lower band 82 is tightened and the presser member is carried in the opposite direction with the lower rotating pulley. It will be observed that the handle 46 is moved in the direction that 115 it is desired to move the presser member and that by this movement of the lever the proper pulley is connected to move the presser member in the direction that the hand moves in actuating the lever 70. Now, 120 it will be seen that the elongated slot in the outer end of the lever 34 is for the purpose of permitting lateral movement of the lever 70, to which the handle 46 is connected, while retaining operative connection between the handle 46 and the lever 34 so that at the end of the lateral movement of the lever 70, said handle may be depressed to operate the lever 34 and thus cause a tripping of the clutch on the main shaft of the 125 130

machine, by which a pressure applying operation is produced.

In the operation of the machine, work is placed upon the work supporting bed 6 and the presser member is moved to one side to permit light to reach the work and to provide space for the manipulation of the work and of the die in locating the latter in desired relation to the work. When the work 10 is properly arranged, the presser member is swung to operative position, the operator grasping the handle 46 and moving it in the direction that he desires the presser member to move whereupon the power means is connected to the presser member to assist the operator in moving the presser member, the construction and arrangement being such that the presser member follows the hand of the operator with the very minimum of effort 20 on his part. As the presser member is approaching the die and without waiting until it is directly over the die, the machine is tripped by depressing the handle 46 whereupon a pressure applying operation 25 takes place, thus forcing the die through the work. The machine is provided with a brake mechanism indicated at 90 and disclosed in the patent to Eaton No. 1,004,757, granted October 3, 1911, which makes it possible 30 to trip the clutch while the presser member is still moving laterally, as described, the brake operating to stop the lateral movement just as the presser member is about to strike the die, thus preventing 35 the striking of a glancing blow. It should be pointed out that as the handle 46 is depressed its movement laterally is terminated, while the presser member continues to move under its acquired momentum with the result 40 that it almost instantly disconnects itself from the pulley which was moving it. After the pressure applying operation, the presser member is swung away from over the die by pressing laterally on the handle 45 46 in whichever direction it is desired that the presser member shall move, whereupon the proper pulley is connected to move the presser member. If desired the presser member may be moved very rapidly away 50 from over the die by pressing firmly in a lateral direction on the handle 46, in which case it becomes necessary to check the lateral movement of the presser member when it has reached the position selected by moving 55 the handle 46 in the opposite direction, whereupon the other pulley is at once applied to the presser member as a brake device to bring it to rest.

Having described my invention, what I 60 claim as new and desire to secure by Letters Patent of the United States is:—

1. In a machine of the class described, a work supporting bed, a presser member, power means for moving the presser member 65 horizontally into and out of operative

position over the bed, and means mounted on the presser member for controlling said power means.

2. In a machine of the class described, a work supporting bed, a presser member, a support at one side of the bed for supporting said member, power means for moving the presser member into and out of operative position over the bed, and means mounted on the presser member for controlling said power means.

3. In a machine of the class described, a work supporting bed, a presser member movable toward and from said bed in pressure applying operations and also laterally 80 from and into operative position over the bed, power means for moving the presser member from and into operative position over the bed, and means mounted on the presser member for controlling the presser member in its pressure applying operations and for controlling also said power means.

4. In a machine of the class described, a work supporting bed, a presser member movable toward and from said bed in pressure applying operations and also laterally above the bed into the desired operative position, power means for moving the presser member laterally into operative position over the bed, and means mounted on the 95 presser member for controlling the presser member in its pressure applying operations and for controlling also said power means.

5. In a machine of the class described, a work supporting bed, a presser member, and power means for moving the presser member into and out of operative position over the bed comprising a constantly driven endless cable, and pulleys arranged to be operatively connected to the presser member and to be driven constantly in opposite directions by said cable so that upon selectively connecting the pulleys to the presser member the latter may be moved in the desired direction over the bed.

6. In a machine of the class described, a work supporting bed, a presser member, and power means for moving the presser member laterally over the bed, comprising a constantly driven cable, and pulleys arranged to be operatively connected to the presser member and to be driven in opposite directions by said cable so that upon selectively connecting the pulleys to the presser member the latter may be moved in 115 the desired direction over the bed.

7. In a machine of the class described, a work supporting bed, a presser member movable over the bed, a post for supporting said presser member, said presser member being movable about the axis of said post, pulleys mounted upon said post and arranged to be driven constantly in opposite directions, and means for selectively connecting the pulleys to the presser member 120

so that the latter may be moved in the desired direction over the bed.

8. In a machine of the class described, a work supporting bed, a presser member, a post for supporting the presser member so that the latter is movable about the axis of the post, pulleys mounted on the post and arranged to be driven constantly in opposite directions, and means mounted on the presser member for selectively connecting the pulleys to the presser member to move the same in the desired direction.
9. In a machine of the class described, a work supporting bed, a presser member movable toward and from the bed in pressure applying operations, a post supporting said presser member for movement about the axis of the post, a pulley mounted on the post and constantly driven in one direction, and means for operatively connecting the presser member to the pulley to move the presser member in the direction of rotation of the pulley.
10. In a machine of the class described, a work supporting bed, a presser member, a post supporting the presser member for rotation about the axis of the post, a pulley mounted on the post and arranged to be driven constantly in one direction, a lever mounted in the presser member, and a band connected to the presser member and to the lever and passing around said pulley, the arrangement being such that movement of the lever tightens the band about said pulley and causes the presser member to move in the direction of rotation of said pulley.
11. In a machine of the class described, a work supporting bed, a presser member, a post for supporting the presser member for rotation about the axis thereof, a pulley mounted on the post, means for constantly driving said pulley, a band connected to the presser member and passing around said pulley, and means for tightening the band to cause the presser member to move with the pulley in the direction of rotation thereof.
12. In a machine of the class described, a work supporting bed, a presser member, a post for supporting the presser member for rotation about the axis thereof, a pulley mounted on the post, means for constantly driving said pulley, and means on the presser member for operatively connecting the presser member to said pulley.
13. In a machine of the class described, a work supporting bed, a presser member, a post for supporting the presser member for movement over the bed, power means including a pulley mounted on the post for moving the presser member about the axis of the post, and means mounted on the presser member for controlling said power means.
14. In a machine of the class described, a work supporting bed, a presser member, a post for supporting the presser member for movement laterally over the bed, power means for causing pressure applying movements of the presser member, power means including a pulley mounted on the post for moving the presser member about the axis of the post, and means mounted on the presser member for controlling both said power means.
15. In a machine of the class described, a work supporting bed, a presser member, a post supporting the presser member for rotation about the axis of the post, a pulley on the post, means for driving the pulley, and means carried by the presser member for engaging the moving pulley to cause the presser member to move with the pulley into position over the work supporting bed.
16. In a machine of the class described, a work supporting bed, a presser member, a post for supporting the presser member for rotation about the axis of the post, a pulley on the post, means for driving the pulley, a lever carried by the presser member, and means for operatively connecting the lever to the pulley so that upon movement of the lever the presser member is operatively connected to the pulley to move therewith into position over the work supporting bed.
17. In a machine of the class described, a work supporting bed, a presser member, means for causing pressure applying movements of the presser member, means for controlling said first-mentioned means comprising a member mounted on the presser member and provided with a handle, a lever mounted on the frame of the machine, and a connection between the member and lever having portions so arranged and proportioned that the handle portion of the lever remains stationary during a pressure applying movement of the presser member.
18. In a machine of the class described, a work supporting bed, a presser member, means for causing pressure applying movements of the presser member, and means for controlling said first-mentioned means comprising a lever mounted on the presser member, and a lever mounted on the frame of the machine and operated from the first-mentioned lever, the construction and arrangement being such that the handle portion of the first-mentioned lever remains stationary during a reciprocation of the presser member.
19. In a machine of the class described, a work supporting bed, a presser member movable toward and from the bed in pressure applying operations, power means for moving the presser member in pressure applying operations comprising a main shaft and a clutch thereon, and a starting mechanism for tripping said clutch, comprising a lever pivoted on the frame of the machine and having an arcual portion extending

ing over the presser member, and a second lever mounted on the presser member and carrying a single roll to engage one surface only of the arcual portion of the first-mentioned lever.

20. In a machine of the class described, a work supporting bed, a presser member movable toward and from the bed, power means for moving the presser member comprising a main shaft and a clutch mechanism for said shaft, starting mechanism for controlling said clutch comprising a member mounted on the presser member and having a handle by which it may be actuated, a clutch-operating lever mounted on the frame of the machine, and a member geared to the first-mentioned member and operatively connected to the lever and having portions dimensioned with respect to 15 corresponding portions of the first-mentioned member so that the handle remains stationary in space during the pressure applying movement of the presser member.

21. In a machine of the class described, a work supporting bed, a presser member movable toward and from the bed, power means for moving the presser member comprising a main shaft and a clutch mechanism for said shaft, and starting mechanism for controlling said clutch, comprising levers mounted on the presser member to move therewith, a handle by which they may be actuated, the levers each having arms of the same horizontal length 35 whereby the handle remains stationary in space during a pressure applying movement of the presser member.

22. In a machine of the class described, a work supporting bed, a presser member, a post for supporting the presser member for rotation about the axis thereof, a device having surfaces constantly driven in opposite directions, and means for connecting the presser member selectively with the 45 surfaces to move the same in the desired direction.

23. In a machine of the class described, a work supporting bed, a presser member, a post for supporting the presser member for 50 rotation about the axis thereof, a continuously driven device mounted on the post and providing a surface to which the presser member may be connected, and means on the presser member for operatively connecting the presser member to said surface.

24. In a machine of the class described, a work supporting bed, a presser member movable toward and from said bed in pressure applying operations and also laterally 60 from and into operative position over the bed, power means for moving the presser member from and into operative position over the bed, and manually operable means mounted on the presser member for con-

trolling the presser member in its pressure applying operations and for controlling also 65 said power means, the construction and arrangement being such that movement of the manually operable means in the desired direction by the operator results in the connection of said power means to the presser member so that the presser member follows the hand of the operator without appreciable effort on his part.

25. In a machine of the class described, a work supporting bed, a presser member, a post for supporting the presser member so that the latter is movable about the axis of the post, pulleys mounted on the post and arranged to be driven constantly in opposite directions, and manually operable means for selectively connecting the pulleys to the presser member to move the same in the desired direction, the construction and arrangement being such that either pulley 85 may be connected to the presser member to act as a brake for the presser member moving under momentum acquired by connection with the other pulley.

26. In a machine of the class described, a work supporting bed, a presser member movable toward and from the bed in pressure applying operations, power means for moving the presser member in pressure applying operations comprising a main shaft 90 and a clutch thereon, and a starting mechanism for tripping said clutch, comprising a lever pivoted on the frame of the machine and having an arcual portion extending over the presser member, and a member 95 mounted on the presser member and carrying means for engaging one surface only of the arcual portion of said lever.

27. In a machine of the class described, presser members, power means for causing 105 relative movement of the presser members toward and from each other in pressure applying operations, power means for moving the presser members relatively to each other in a lateral direction, and a single means 110 movable with one of the presser members for controlling both said power means.

28. In a machine of the class described, presser members, power means for causing 115 relative movements of the presser members along paths angularly related to each other, and a single means movable with one of the presser members for controlling said power means.

29. In a machine of the class described, a work supporting bed, a presser member, power means for swinging the presser member into and out of operative position over the bed, and a manually operable lever mounted on the presser member and movable 120 with respect to the presser member operatively to connect the power means to the presser member and thereafter movable 125

with the presser member so that the hand of the operator moves with the presser member as the latter moves to operative position.

30. In a machine of the class described, 5 a work supporting bed, a presser member, power means for moving the presser member into and out of operative position over the bed, said means comprising a constantly rotating pulley, a band connected to the 10 presser member and passing round the pulley, and a manually operable lever movable with respect to the presser member and having a connection with the band whereby the presser member may be operatively connected with the pulley.

31. In a machine of the class described, a work supporting bed, a presser member, power means for moving the presser member into and out of operative position over 20 the bed, said means comprising a constantly rotating pulley and a band connected to the presser member and passing round the pulley, power means for causing pressure applying operations of the presser member, a 25 lever mounted on the presser member and having a connection with the band whereby the presser member may be operatively connected with the pulley, and a handle for controlling said lever and said last-mentioned power means.

32. In a machine of the class described, a work supporting bed, a presser member, means for causing pressure applying movements of the presser member, means for 35 controlling said first mentioned means comprising a lever mounted on the presser member, a handle for the lever, a lever mounted on the frame of the machine, a second lever mounted on the presser member operatively 40 connected to the other two levers and having arms so dimensioned with respect to the arms of the first-mentioned lever that the handle remains stationary in space during a pressure applying movement of the 45 presser member.

33. In a machine of the class described, 50 presser members relatively movable toward and from each other in pressure applying operations and also relatively movable laterally of each other into and out of operative relation, power means for causing relative lateral movement of the presser members, means for stopping said relative lateral movement of the presser members, and 55 manually operable means mounted on one of the presser members for controlling said stopping means so as to stop said lateral movement at the will of the operator.

34. In a machine of the class described, 60 presser members relatively movable toward and from each other in pressure applying operations and also movable relatively laterally of each other into and out of operative relation, power means for causing rela-

tive lateral movements of the presser members, a braking means for checking relative lateral movement of the presser members, and a manually operable lever mounted on one of the presser members for controlling said braking means.

35. In a machine of the class described, 70 presser members relatively movable toward and from each other in pressure applying operations and also relatively movable laterally of each other into and out of operative 75 relation, power means for causing relative lateral movement of the presser members, and means comprising a brake band under the control of the operator for checking the relative lateral movements of the 80 presser members.

36. In a machine of the class described, a work supporting member, a presser member movable toward and from the work supporting bed in pressure applying operations, 85 power means for swinging the presser member laterally of the bed into and out of operative position with respect to the work on the bed, and means mounted on the presser member and under the control of the 90 operator for yieldingly checking the lateral swinging movement of the presser member.

37. In a machine of the class described, a work supporting bed, a presser member movable toward and from the bed in pressure 95 applying operations and movable laterally of the bed into and out of operative position with respect to work on the bed, power means for causing pressure applying operations, power means for moving the presser 100 member laterally of the bed, means for checking the lateral movement caused by the last mentioned power means, and a manually operable member mounted on the presser member for controlling all three of the last 105 mentioned means.

38. In a machine of the class described, a work supporting bed, a presser member movable toward and from the bed in pressure applying operations and movable laterally of the bed into and out of operative position with respect to work on the bed, power means for causing pressure applying operations, power means for initiating lateral movements of the presser member, frictionally operated means for checking the lateral movements of the presser member, and a manually operable lever mounted on the 115 presser member for controlling the two last mentioned means.

39. In a machine of the character described, a work supporting bed, a presser member movable toward and from the bed in pressure applying operations and movable laterally of the bed into and out of operative 125 position with respect to work on the bed, power means, comprising a constantly rotating pulley and a band for connecting the

same operatively to the presser member, for causing lateral movements of the presser member, and a second pulley arranged to be operatively connected to the presser member 5 for checking the lateral movement of the presser member at the will of the operator.

40. In a machine of the class described, a work supporting bed, a presser member, a post at one side of the bed for supporting the 10 presser member, power means for moving the presser member about the axis of the post into and out of operative position over the bed, and a manually operable member mounted on the presser member for controlling said power means.

41. In a machine of the class described, a work supporting bed, a presser member, power means for swinging the presser member into and out of operative position with 20 respect to work located on the bed, and a member movable with respect to the presser member operatively to connect the power means to the presser member and thereafter movable with the presser member so that 25 the hand of the operator moves with the presser member as the latter moves to operative position.

42. In a machine of the class described, a work supporting bed, a presser member, a 30 support upon which the presser member is pivoted, power means for swinging the presser member into and out of operative position with respect to work located on the bed, and a manually operable member movable 35 laterally with the pressure member from one side of the bed to the other side thereof and operable to connect the power means with the presser member.

43. In a machine of the class described, a 40 work supporting bed, a presser member, a post for rotatably supporting the presser member, power means comprising a cable for causing movement of the presser member laterally over the bed into and out of operative position with respect to work located 45 on the bed, and a manually operable member movable relatively to the presser member for causing an operative connection of the presser member and said power means 50 and subsequently movable with the presser member as the latter moves over the bed so that the hand of the operator moves with the presser member to control the latter.

44. In a machine of the class described, a 55 work supporting bed, a presser member, a support at one side of the bed for supporting said member, power means at one side of the bed for moving the presser member into and out of operative position with respect to 60 work located on the bed, other power means for causing pressure applying operations on the presser member also located at one side of the bed, the construction and arrangement being such that the space above the bed is

unobstructed when the presser member is displaced laterally to uncover the work, and a manually operable member mounted on the presser member for controlling both of said power means. 65

45. In a machine of the class described, 70 presser members relatively movable toward and from each other in pressure applying operations, power means for causing such relative movement of the presser members, means for controlling said power means 75 comprising a lever mounted on the frame of the machine, and a manually operable lever mounted on the movable presser member and operable to effect the operation of the first mentioned lever.

46. In a machine of the class described, 80 presser members relatively movable toward and from each other in pressure applying operations and also laterally of each other into and out of operative relation, power 85 means for causing pressure applying operations, means for controlling said power means comprising a lever mounted on the frame of the machine, and a manually operable member pivoted to the movable 90 presser member and having a connection with said lever throughout the lateral movement of the movable presser member whereby operation of the power means may be initiated in whatever position the movable 95 presser member may occupy with respect to the other presser member.

47. In a machine of the class described, 100 presser members relatively movable toward and from each other in pressure applying operations, power means for causing such relative movement of the presser members, means for controlling said power means 105 comprising a member pivoted on the frame of the machine, and a manually operable member mounted on the movable presser member and having a single point connection with the pivoted member to effect operation thereof.

48. In a machine of the class described, 110 a work supporting bed, a presser member, a support for the presser member located at one side of the bed, power means comprising a cable for causing movement of the presser member laterally over the bed into and out of operative position with respect to work located 115 on the bed so that the space above the work may be unobstructed when the presser member is displaced laterally, and a manually operable member movable relatively to the presser member for causing an operative connection of the presser member and said power means and subsequently movable with the presser member as the latter moves over the bed so that the hand 120 of the operator moves with the presser member to control the latter.

49. In a machine of the class described, a

work supporting bed, a presser member, a support at one side of the bed for supporting said member, power means at one side of the bed for moving the presser member into 5 and out of operative position with respect to work located on the bed, other power means for causing pressure applying operations on the presser member also located at one side of the bed, the construction and arrangement being such that the space above the bed is unobstructed when the presser member is displaced laterally to uncover the work, and a manually operable member movable with the presser member to each 10 operative position of the latter for controlling one of said power means and subsequently movable in another direction to control the other power means.

50. In a machine of the class described, a work supporting bed, a presser member movable toward and from the bed in pressure applying operations, power means for causing such movement of the presser member, a member mounted on the presser member and 25 having a handle adapted to be manipulated by the operator to cause operation of the power means, and means for counteracting movement of the handle due to the mounting of said member on the presser member 30 whereby the handle remains stationary in space during movement of the presser member.

51. In a machine of the class described, a work supporting bed, a presser member movable toward and from the bed in pressure applying operations, power means for causing such movement of the presser member, a starting lever mounted on the frame of the machine for controlling said power means, 35 a member mounted on the presser member and having a handle adapted to be manipulated by the operator to initiate operation of the machine, and a connection between said member and said starting lever constructed 40 to cause movement of the handle toward the presser member progressively with movement of the latter away from the work supporting bed, whereby the handle remains stationary in space.

50 52. In a machine of the class described, a work supporting bed, a presser member movable toward and from the bed in pressure applying operations, power means for causing such movement of the presser member, 55 a starting lever mounted on the frame of the machine for controlling said power means, a member mounted on the presser member and having a handle adapted to be manipulated by the operator to initiate operation of the machine, and a connection between said member and said starting lever constructed 60 to cause an upward movement of the handle relatively to the presser member progressively with the downward movement of the latter and also downward move-

ment of the handle relatively to the presser member during upward movement of the latter whereby the handle remains stationary in space throughout a reciprocation of the presser member.

53. In a machine of the class described, a work supporting bed, a presser member movable toward and from the bed in pressure applying operations, power means for causing such movement of the presser member, a starting lever mounted on the frame of the machine for controlling said power means, a member mounted on the presser member and having a handle adapted for manipulation by the operator to initiate power operation 80 of the machine, and a connection between said member and the starting lever comprising a part which engages the starting lever in such manner that it cannot move down with the presser member and having portions so arranged and proportioned with respect to corresponding portions of the handle member that the handle remains stationary in space during downward movement of the presser member. 90

54. In a machine of the character described, a work supporting bed, a presser member movable toward and from the bed in pressure applying operations and also laterally over the bed into and out of operative 95 relation to work located on the bed, a post for supporting the presser member for swinging movement over the bed, power means concentric with the post for causing swinging movement of the presser member, 100 and a member movable with the presser member and also relatively thereto for controlling the power means.

55. In a machine of the character described, presser members relatively movable 105 toward and from each other in pressure applying operations and also in a lateral direction relatively to each other into and out of operative relation to work located between the presser members, a post for supporting the movable presser member for swinging movement relatively to the other member, power means concentric with the post for causing swinging movement of the movable 110 presser member, and a member movable with the movable presser member and also relatively thereto for controlling said power means. 115

56. In a machine of the character described, a work supporting bed, a presser member movable toward and from the bed in pressure applying operations and also laterally over the bed into and out of operative 120 relation to work located on the bed, power means for moving the presser member along paths angularly related to each other to effect pressure operations upon the work wherever located on the bed, a post for supporting the presser member for swinging movement laterally over the work support- 125 130

ing bed, and a member movable with the presser member and also relatively thereto for controlling said power means.

57. In a machine of the character described, a work supporting bed, a presser member movable toward and from the bed in pressure applying operations and also laterally over the bed into and out of operative relation to work located on the bed, power means for moving the presser member laterally over the bed, a post for supporting the presser member for swinging movement over the bed, clutches and power pulleys concentric with the post for causing swinging movement of the presser member, and a manually operable member movable with the presser member and also relatively thereto for controlling the power means.

58. In a machine of the character described, presser members relatively movable toward and from each other in pressure applying operations and also in a lateral direction relatively to each other into and out of operative relation to work located between the presser members, a post for supporting the movable presser member for swinging movement relatively to the other member, a clutch and a power pulley concentric with the post for causing swinging movement of the movable presser member, and a member movable with the movable presser member and also relatively thereto for controlling said power means.

In testimony whereof I have signed my name to this specification.

WILLIAM B. KING.
